UNITED STATES PATENT OFFICE.

MURDO G. FINLAYSON, OF CHICAGO, ILLINOIS.

FLOOR-STRIP HOLDER.

1,375,043.

Specification of Letters Patent. Patented Apr. 19, 1921.

Application filed August 23, 1919. Serial No. 319,320.

To all whom it may concern:

Be it known that I, MURDO G. FINLAYSON, a citizen of the United States, residing at Chicago, in the county of Cook and State 5 of Illinois, have invented certain new and useful Improvements in Floor-Strip Holders, of which the following is a specification.

This invention relates in general to building constructions, and has more particular 10 reference to the floor supporting construction.

In the construction of both concrete and wooden buildings, it is customary to provide a rough floor over which the finishing floor 15 is laid. The finishing floor is carried by and nailed to strips supported above the rough floor, usually on wooden blocks so that the water, gas and other pipes may be run in any direction above the rough floor 20 and beneath the nailing strips. In lieu of wooden blocks for supporting the nailing strips, metal chairs are sometimes employed which perform the same function as the blocks.

The rough floor, however, is not leveled with any degree of accuracy when laid and it therefore becomes necessary to accurately level the nailing strips upon which the finishing floor is laid. This is most frequently 25 done by lifting the blocks or metal chairs above the surface of the rough floor and filling in beneath these blocks or chairs with plaster or concrete so that the upper faces of the nailing strips are at the requisite 30 level. It frequently happens however, that before the plaster or concrete has hardened, someone will step on the nailing strips or some weight will be imposed thereon which will depress the supporting blocks or chairs 35

40 into the plaster or concrete with the result that some of them will be disposed below the requisite level and with the result that when the finishing floor is laid, it will not be perfectly level or if level when laid, it is 45 insufficiently supported at some places and subsequently sags, and in any event is very creaky.

One of the primary objects of my present 50 invention is to provide a floor strip holder or support on which the floor strips are carried, each holder being vertically adjustable so that the floor strips can be accurately leveled irrespective of irregularities in the 55 rough floor and without employing filling material such as concrete or cement which, when used, is apt to become displaced before

it is hardened and also shrinks in drying so that accurate leveling of the floor strips is disturbed.

Another object of my invention is to provide floor strip holders which will be simple 60 in construction, cheap to manufacture, and which can be quickly and easily put in place and adjusted as required, to bring the floor strips to the desired level.

Other objects and many of the advantages of my invention will be readily appreciated as the same becomes better understood by reference to the following description when considered in connection with the 70 accompanying drawings.

Referring to the drawings, Figure 1 is a fragmentary perspective view of a floor structure embodying my invention.

Fig. 2 is a perspective sectional view 75 showing one of my improved floor strip holders in position.

Fig. 3 is a similar view showing the holder adjusted to another position, and

Fig. 4 is a plan view of one of the holders 80 with a floor strip in position thereon.

Referring now to the drawings in detail, the construction shown comprises a lower or rough floor 5, which may be of any preferred construction, the form selected for the purposes of illustration, being constructed of building tile and concrete, although my invention is equally capable of use in connection with wooden rough floors or other types. The finishing floor 6 is carried upon 85 and nailed to a series of transversely extending nailing strips 7, and my invention is concerned primarily with the supporting of these strips.

My improved floor strip holder is made 90 of metal and consists of the base member 8, the floor strip supporting member 9, and an adjustable connection between these members. The base member 8 in the form selected for illustration herein, is of in- 100verted channel shape provided with laterally extending feet or webs 11 providing a broad substantial support for the base member. These webs or feet preferably, are equipped with cut away portions 12, as 105 shown to facilitate bonding of the holding cement in which they are embedded, but manifestly the webs might be provided with slots, apertures, or other provisions for accomplishing this result, and as a matter of 110 fact, when the devices are to be used in wooden constructions, nail receiving aper-

tures through which the webs may be spiked to the rough floor are preferable. Centrally, the top of the base member is formed to provide a depression 13 preferably square and adapted to receive a nut 14 which is rigidly secured in the depression by spot welding or other provision which will retain the nut in position.

The floor strip supporting member 9 is also channel shaped, but its flanges project upwardly so that the member is proportioned to accommodate the nailing strip 7 which, when seated in the supporting member, is secured therein by nails 15 or other preferred fastening means. The horizontal portion of the upper member is equipped centrally with a downwardly projecting threaded bolt 16 adapted for threaded engagement with the nut 13 in the base member. The lower end of the bolt is preferably enlarged as indicated at 17 so that it can not become unthreaded and accidentally disengaged from the nut 14. When the device is assembled, the bolt 16 is threaded through the nut 13 from beneath and its reduced upper end is extended through an aperture in the upper member 9 where it is rigidly secured by spot welding or riveting.

In the construction of a floor embodying my invention, the floor strip holders are arranged in rows spaced from each other the requisite spacing of the floor strips, and in each row the individual rows are spaced apart a predetermined distance. A floor strip is seated in each row of holders and the holders are secured thereto by the nails 15. In order to level the floor strips, the base of each holder is rotated upon the bolt 16 until the upper face of the strip is in the requisite horizontal plane with the feet of the base member upon the rough floor. By suitably adjusting the individual holders in this manner, the floor strip can be quickly and accurately adjusted to the proper level and when adjusted, it will be rigidly supported by each holder without the employment of filling material such as concrete or the like. For the purpose of retaining the holders in the requisite position, after they have been adjusted they are securely anchored to the rough floor. When the rough floor is of wooden construction, this is accomplished by nailing the bases of the holders to the rough floor. In a fire proof construction embodying a rough floor made of tile, as illustrated in the present drawing, the holders are anchored by filling in around them with cement or concrete 18 which is simply thrown around the holders with a

trowel. Any desired amount of this holding concrete which bonds with the rough floor may be employed, but preferably a sufficient quantity is utilized to fill in the space between the base member and the floor strip supporting member of the holder, as indicated in Fig. 3, thus adding to the rigidity of the floor construction.

It is believed that the construction, the manner of use, and many of the inherent advantages of my invention will be apparent from the foregoing without further description, but it should be manifest that various modifications in the details of structure illustrated and described, may be resorted to without departing from the essence of the invention as defined in the appended claims.

I claim:

1. A floor strip holder, comprising a base member, a floor strip supporting member, and one of said members having fixedly attached thereto a threaded bolt and the other being provided with a tapped opening for threaded engagement with said bolt whereby the distance between said members may be adjusted.

2. A floor strip holder, comprising a base member having a nut fixedly attached thereto, and a floor strip supporting member having a bolt fixedly attached thereto to be threaded into said nut for varying the distance between said members.

3. A floor strip holder, comprising a base member provided with a central tapped aperture, a floor strip supporting member provided with a seat for a floor strip, a threaded bolt rigidly secured to and projecting downwardly from said seat member and adapted to be threaded into said base member, and means for attaching a floor strip to said seat member.

4. A floor strip holder, comprising two substantially channel shaped members, means for securing a floor strip to one of said members, and adjustable means positively connecting said members together so as to preclude relative movement therebetween in any adjusted position.

5. A floor strip holder, comprising a base member and a floor strip supporting member, means for securing a floor strip to said floor strip supporting member, and adjustable means positively connecting said members together so as to preclude relative movement therebetween in any adjusted position.

MURDO G. FINLAYSON.
